United States Patent Office.

RAPHAEL MORITZ SELDIS, OF NEW YORK, N. Y.

Design No. 4,863, dated May 2, 1871.

DESIGN FOR A MUFF AND COLLAR-BOX.

The Schedule referred to in these Letters Patent and making part of the same.

To all whom it may concern:

Be it known that I, RAPHAEL MORITZ SELDIS, of New York city, in the county and State of New York, have invented a new and original Design for a Muff and Collar-Box; and I do hereby declare that the following is a full, clear, and exact description thereof, which will enable others skilled in the art to make and use the same, reference being had to the accompanying drawing forming part of this specification.

Figure 1 represents a vertical section of my design for a muff and collar-box.

Figure 2 is a top view of the same, showing the covers swung open.

Similar letters of reference indicate corresponding parts.

This invention relates to a new design of a double box for muff and fur collar, and to a new design for the cover or covers of the same.

The entire box A is of rectangular shape, and contains two upright receptacles, a and b, of which the first is cylindrical for the reception of the muff, and the second prismatic and narrow, for the reception of the collar.

Each of these receptacles or compartments has its own cover, c being the cover to the muff-chamber a, and d that for the collar-chamber b. The contents of the one chamber can thus be reached without interfering with those of the other.

Each of the covers is hinged to the box, and has a flange or rim, e, which enters its chamber, as is clearly shown in fig. 1. Such hinged covers, entering the boxes with their rims instead of surrounding them, as usually, are applicable to all fur-boxes of suitable form.

I claim as my invention—

1. A double box, containing separated chambers for the muff and collar, with their own covers c d, as described.

2. The design for the cover of a fur-box, as shown.

RAPHAEL MORITZ SELDIS.
